COMBINED APPLICATOR AND SCALP MASSAGER

Samuel L. Gerson, 229 Thomas Drive, Wilmington, Del.

Filed May 31, 1960, Ser. No. 60,788

Term of patent 14 years

(Cl. D83—1)

FIG. 1.

FIG. 2.

FIG. 3.

FIG. 4.

FIG. 5.

FIG. 1 is a top plan view of a combined applicator and scalp massager embodying my new design;

FIG. 2 is a side view in elevation thereof;

FIG. 3 is a bottom plan view thereof;

FIG. 4 is a perspective view thereof; and

FIG. 5 is a cross-sectional view thereof taken through line 5—5 of FIG. 1.

I claim:

The ornamental design for a combined applicator and scalp massager, as shown.
